UNITED STATES PATENT OFFICE.

WILLIAM F. FOCHA, OF RICHMOND, CALIFORNIA.

HAIR-PIN.

1,256,005.

Specification of Letters Patent. Patented Feb. 12, 1918.

Application filed September 13, 1917. Serial No. 191,239.

To all whom it may concern:

Be it known that I, WILLIAM F. FOCHA, a citizen of the United States, residing at Richmond, in the county of Contra Costa 5 and State of California, have invented certain new and useful Improvements in Hair-Pins, of which the following is a specification.

This invention relates to hair pins, and 10 more particularly to a wire hair pin of that type in which two prongs are provided, these prongs being of twisted or undulating configuration so as to prevent the pin from being accidentally withdrawn from a 15 person's hair.

One of the main objects of the invention is to provide a pin of the character stated which may be used for securing a veil or similar article to the wearer's hair, the 20 prongs of the pin being so relatively disposed as to be locked when twisted together so as to effectually prevent detachment of the same. A further object is to provide a pin in which the prongs are of a more or 25 less wavy outline so as to prevent withdrawal of the pin from the hair when used in the ordinary manner, these prongs being twisted so as to form oppositely directed elongated spirals, the undulations of the 30 spirals gripping the hair in the same manner as the undulations of the so called "crinkly" hair pin, with the exception that being oppositely directed the pin is more firmly secured in the hair. Further objects will appear from the detail description. 35

In the drawings:

Figure 1 is a top plan view of a pin constructed in accordance with my invention 40 in locked position.

Fig. 2 is a similar view of the pin in open position,

Fig. 3 is an end view looking at the outer or free ends of the prongs,

Fig. 4 is a side view of the pin locked.

Fig. 5 is a similar view open.

The pin is formed from a continuous piece of metal or wire bent into an elongated U-shape having the arms or prongs 50 1 and 2. The prong 1 of the pin is turned outward in an elongated spiral about its axis, as indicated by the arrow in Fig. 2. The prong 2 is also turned inward about its axis in spiral shape as indicated. The 55 prong 1, due to the manner in which it is bent, is provided with the alternately dis-

posed and oppositely directed depressions 3, 4, 5, and 6, and the corresponding raised portions 3^a, 4^a, 5^a, and 6^a, respectively. Adjacent its outer or free end, prong 1 is bent 60 to provide a relatively sharp or sudden rounded portion 7, and a straight locking portion 8 contiguous thereto. The bend 6 and raised portion 6^a adjacent the portion 7 is also somewhat sharper than the other 65 bends of the prong 1, for a purpose to be later disclosed. The prong 2 is provided with the depressions 9, 10, 11, and 12, and the corresponding swells or raised portions of prong 1 and directed oppositely thereto. 70 This prong is also provided with the sharply bent portion 7^a and the contiguous straight locking portion 8^a corresponding to the portions 7 and 8 of prong 1 and oppositely directed thereto.

75 Due to the manner in which the two prongs are bent, by grasping the free ends of the prongs between the thumb and forefinger of the right hand, and the upper end or head of the pin between the thumb and forefinger of the left hand, and turning the pin in a counter-clockwise direction the two prongs will be twisted together so as to bring the raised portions or swells of one prong into the depressions of the other 80 85 prong. The sharply bent portion or swell 7 of prong 1, and the corresponding portion 7^a of prong 2 fit snugly into each other so as to bring the straight portions 8 and 8^a into overlapping locking engagement, 90 thus effectually preventing unwinding of the prongs. When it is desired to unlock the pin, it is grasped in the same manner as above and turned in a clockwise direction so as to untwist the prongs. When open, 95 the pin is well adapted to be used in the ordinary manner for a hair pin, the undulations of the prongs serving to prevent the pin from becoming accidentally disengaged from the hair of the wearer. When locked 100 in the manner described, the pin is well adapted to secure a veil or the like to the wearer's hair, and it is impossible for it to become accidentally unlocked due to the manner in which the prongs are secured, as 105 it is necessary to first move the locking portions 8 and 8^a out of engagement before the prongs 1 and 2 can be untwisted or released from each other.

110 A hair pin constructed in this manner may be quickly and easily manufactured at very small cost and, in addition to being

well adapted for use in the ordinary manner as a hair pin, it also provides very simple and efficient means for securing an article to a person's hair.

5. What I claim is:—

A hair pin having two spaced arms, each of said arms being bent outwardly spirally about its axis so as to form a series of undulations, the arms being coiled in the same 10 direction about their axes and the undulations of one arm corresponding with those of the other arm whereby, when the arms of the pin are twisted together, the undulations of these members interengage and 15 operate to lock them in this position, each

of said arms being further provided, at its free end portion, with a relatively sharply curved portion and a straight locking portion contiguous thereto, the said curved portions being so related as to engage and 20 bring the said straight locking portions into overlapping relation when the arms of the pin are twisted together.

In testimony whereof I affix my signature in presence of two witnesses.

WILLIAM F. FOCHA.
